UNITED STATES PATENT OFFICE.

LOUIS F. E. VONDRAČEK, OF VALLEY CITY, NORTH DAKOTA.

MOTOR-DRIVEN VEHICLE.

1,107,563.

Specification of Letters Patent. Patented Aug. 18, 1914.

Application filed December 6, 1913. Serial No. 805,126.

To all whom it may concern:

Be it known that I, LOUIS F. E. VONDRAČEK, a citizen of the United States, residing at Valley City, in the county of Barnes 5 and State of North Dakota, have invented certain new and useful Improvements in Motor-Driven Vehicles, of which the following is a specification, reference being had to the accompanying drawings.

10 This invention relates to certain improvements in motor driven vehicles and has relation more particularly to a device of this general character especially designed and adapted for use in travel over snow or ice 15 and the object of the invention is to provide a device of this general character having novel and improved means whereby the same may be propelled at differing speeds through the medium of mechanism coacting 20 with atmospheric resistance.

The invention consists in the details of construction and in the combination and arrangement of the several parts whereby certain important advantages are attained 25 and the device is rendered simpler, less expensive and otherwise more convenient and advantageous for use, all as will be herein-after more fully set forth.

The novel features of the invention will 30 be carefully defined in the appended claims.

In order that my invention may be the better understood, I will now proceed to describe the same with reference to the accompanying drawings, wherein—

35 Figure 1 is a view in side elevation of a vehicle constructed in accordance with an embodiment of my invention, the inclosing body and door therefor being indicated by dotted lines; Fig. 2 is a view in top plan 40 of the device as illustrated in Fig. 1, with certain of the parts omitted and shown in section; Fig. 3 is an enlarged fragmentary view in elevation, with parts broken away, of the driving connection, as herein embodied; Fig. 4 is a view partly in section and 45 partly in top plan, illustrating in detail the friction wheel herein embodied; Fig. 5 is an enlarged sectional view taken on the line 9—9 of Fig. 3; Fig. 6 is a sectional view

taken substantially centrally through the 5 operative connection between the propeller shaft and the vertical shaft, as herein embodied; Fig. 7 is a fragmentary view in top 10 the supporting frame for the propeller; Fig. 8 is a transverse section, on an enlarged scale, of a portion of 55 15 the propeller; Fig. 9 is a transverse section, on an enlarged scale, through one of the runners, herein embodied.

As disclosed in the accompanying drawings, 1 denotes the frame of my improved 60 vehicle which may be of any ordinary or preferred material and of any desired configuration but, as herein shown, comprises side sills 2—2 formed preferably of metal, angular in cross section and united at predetermined points throughout their length by the transverse beams or bolsters 3—3 reinforced by the brace members 4—4. Suitably connected with the side sills 2—2 adjacent the forward end thereof are the semi- 65 elliptical springs 5—5 operatively connected with such sills through the medium of the clamping members or clevises 6—6 and to the transversely disposed front supporting shaft or axle 7. 70

Pivotedly engaged with each extremity 75 of the shaft 7 is a hub member 14 herein shown as held against displacement therefrom through the medium of the clamping or retaining member 15 and operatively connected with such hub 14 through the medium of the arms 16 are the runners 17. While the runners 17 may be of any ordinary or preferred construction, I find it of advantage to provide such runner with a 80 demountable shoe 18, herein shown as held in operative position against the under surface of the runner through the medium of the rims 19 provided with inwardly directed flanges 20 adapted to overlie the shoe 18 and effectively clamp the same against the runner 17. The rims 19 are provided with the upwardly projected flanges 21 through which the retaining means 22, herein shown as an elongated bolt, is adapted to pass, 85 such bolt being directed transversely through the runners 17 and being operatively engaged by a bur or nut comprised 90 in the bolt. 95

in such retaining means. By this arrangement it will be readily perceived that a shoe after becoming unduly worn may be readily and conveniently replaced with facility 5 and despatch.

Adjacent the rear end of the frame, the sills 2-2 are provided with laterally directed spring supports 23 to which are suitably secured the elliptical springs 24 which 10 in turn are suitably clamped to the rear axle 25 disposed transversely of the frame 1 and on which are suitably affixed the hubs 26 of the skees 27 constructed substantially in the same manner as the skees on the forward 15 or front axle.

Projecting upwardly and rearwardly from the forward portions of the side sills 2 are the supporting arms 28 operatively connected at their upper ends to the substantially horizontally disposed elongated member 29 terminating in a suitably formed bearing 30 for the propeller 31 whereby the force generated or created by the propeller 31 is transmitted to the frame 1. As herein disclosed 20 the propeller 31 comprises a plurality of blades 32 preferably four in number of proper transverse pitch and having their extremities incased in a metallic casing in order to reduce to a minimum the possibility of 25 injury thereto, the inner extremities being suitably secured to a metallic disk or plate 33 having produced in its axial center an opening 34 angular in cross section, through which is adapted to pass a shaft 35 of similar cross section and through the medium of 30 which the propeller 31 is adapted to be rotated. The plate or disk 33 is substantially in contact with an adjacent face of the bearing 30 and is held against displacement from 35 such shaft 35 through the medium of the retaining member 36, herein shown as in the nature of a nut or bur, in threaded engagement with the outer extremity of such shaft 35.

45 In order to reduce to a minimum any resultant friction between the plate 33 and the bearing 30, I interpose therebetween the anti-friction members 37, herein shown as in the nature of ball bearings, operatively positioned in suitable annular race-ways produced in the adjacent faces of the plate 33 and the bearing 30.

Adjacent its inner extremity the shaft 35 has fixed thereto, as herein disclosed, a bevelled gear 38 adapted to mesh with the bevelled gear 39 fixed to the upper extremity of a vertically disposed shaft 40, such gear 39 being of greater diameter than the gear 38 whereby it will be perceived that the shaft 40 50 will be caused to rotate at a much higher speed than the rotation of the shaft 35.

In order to reduce to a minimum any resultant friction between the gears 38 and 39 with the adjacent portions of the bearing 30,

I provide the rear and under faces respectively of such gearings with the conical projections 41 adapted to bear against the roller bearings 42 suitably mounted within such bearing 30. I also find it of advantage to have the shafts 35 and 40 projected through plain bearing surfaces in such bearing 30 and through fiber washers such as felt so that suitable lubricant may be placed within the bearing 30 to facilitate the operation of the gears 38 and 39. The lower extremity of the shaft 40 is mounted in a bearing 101 carried by the rear portion of the frame 1.

Keyed to the shaft 40 so as to rotate therewith but capable of movement longitudinally thereof is a wheel 43, such coaction between the wheel 43 and the shaft 40 being disclosed in the drawings as created by having such shaft 40 angular in cross section with the wheel 43 provided at its axial center with an opening similar in cross section as the shaft, 85 although I do not wish to be understood as limiting myself to this exact construction as the well known idea of a feather may be employed if the requirements of practice should so dictate. Detachably connected 90 with the wheel 43 and snugly bearing against the periphery thereof is an annular ring 44 having produced in its periphery the holes or pockets 45 adapted to create a suction action when such ring is in operative engagement with the disk 46, to be hereinafter referred to. By employing the ring 44 it is to be observed that the same can be readily and conveniently replaced should it become unduly worn as to not operate with the requisite facility.

The disk 46 is mounted for endwise movement upon an extremity of the shaft 47 but is adapted to rotate therewith and, as herein disclosed, this coaction is afforded by having such extremity of the shaft 47 angular in cross section, while the disk 46 is provided at its axial center with an opening of similar configuration in cross section. The shaft 47 constitutes the driving shaft and is 110 operatively connected with a suitable motor 48 preferably of an internal combustion type and suitably positioned upon the frame 1. The driving or friction surface of the disk 46 is provided with a removable plate 49 115 which is removably held upon such disk 46 through the medium of the clips 102, such plate 49 being also adapted to be removed after becoming unduly worn. Also slidably mounted upon the angular extremity of the shaft 47 is a collar or slide 50 positioned rearwardly of the disk 46 and interposed between such disk and collar or slide is the expansible member 51, herein shown as a coil spring, which is adapted to maintain the disk 46 in operative engagement or contact with the wheel 43, hereinbefore referred to, and by adjusting the collar or slide 50

engaged upon the shaft 47, it will be easily perceived that the tension with which the disk 43 contacts with the wheel 45 may be readily and conveniently adjusted as to the requirements of practice may dictate.

While the collar or slide 50 may be moved upon the shaft 47 in a manner as will operate with facility I prefer to employ the arrangement disclosed in the accompanying drawing 5, wherein the collar or slide 50 is provided intermediate its length with a polished sleeve 52 in which the collar or slide 50 is freely rotatable and this sleeve is provided with the oppositely directed projections 54 adapted to be engaged by the fork 55 carried by the rock arm 53 mounted intermediate its length upon the short shaft 57, the upper extremity of the rock arm 53 is in pivotal engagement with an elongated link or rod 58 such link or rod being also in pivotal engagement with a lever 59 mounted for working movement and adapted to be operated by the foot of an occupant of the vehicle.

25 In order to further support the shaft 47, I have the same inserted through the bearing 63 which is herein shown as supported by swinging movement in a vertical plane upon a strap 64 extending transversely of the frame 1. As herein illustrated the bearing 63 is provided with the oppositely directed trunnions 65 which are adapted to be mounted in the properly spaced brackets 66 suitably secured to the strap.

35 As is self-evident the speed with which the shaft 47 may be moved to reduce or increase in the adjustment of the wheel 45 relative to the disk 43 and while this engagement may be created in any manner as may be desired I prefer to employ the arrangement as herein embodied and wherein such disk is provided with the high extension 67 provided with an annular channel 68 in which is loosely accommodated a strap or 40 collar 69 provided with the oppositely directed projections or fingers 71 adapted to be pivotally engaged by the straps 66 which straps are in turn in pivotal engagement with the webs 71. The webs 71 are in pivotal engagement with a collar or bearing 72, one of such webs 71 being of greater length than the second web and projecting a predetermined distance beyond the pivotal mounting, such projected end portion being 45 engaged by a link 73 operatively connected with a crank 70 carried by a short rock shaft 50, which shaft has in operative connection therewith the elongated lever or link 52 in proper connection with a foot lever 59 suitably carried by the frame 1.

55 The feature 1, as herein disclosed, may be defined as wherein a body 81 of simple construction is supported in a forward and slightly inclined position 26 so that the forward 60 movement of the vehicle may be controlled by a structure 82 of the body 81 so that the body 81 is effectively positioned against the elements, a suitable seat 83 on the body being carried by the frame with the body 81, as is believed to be obvious, it being understood that the 70 rock arm or levers 53 and 59 are positioned in such relation thereto as to be readily and conveniently operated by the foot of the occupant.

As herein disclosed, I have positioned to the left of the body 81 and extending upwardly on an incline toward the seat a tubular shaft or housing 88 having suitably affixed to its upper end portion the steering wheel 89, such tubular shaft or housing 88 being suitably connected with the runners 17 so as to permit the same to be moved about their pivot in order to properly guide the vehicle.

Extending through the tubing or housing 88 is the controlling throttle rod 97 for the engine, such rod having at its upper end a laterally directed operating member 98. In order to heat the interior of the body of the vehicle, I find it of advantage that the muffler 93 see the engine be located within the body as is particularly shown in the drawings. I also desire to have suitably positioned within the body a suitable supply tank 100 for the fuel which may be conveyed to the carburetor of the motor in any desired manner.

From the foregoing description it is thought to be obvious that a vehicle constructed in accordance with an embodiment of my invention is of an extremely simple and comparatively inexpensive nature and is particularly well adapted for use by reason of the convenience and facility with which it may be caused to travel at varying speeds and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising a body, runners on which such body is supported, a frame projecting upwardly and rearwardly from the front end of the body, a horizontally disposed elongated member secured to the upper extremity of the frame and projecting rearwardly of the body, propelling means operatively supported by the free extremity of the elongated member, and means for operating such propelling means.

2. A device of the character described comprising a body, runners on which such body is supported, a frame projecting upwardly and rearwardly from the front end of the body, a front leg carried by the free

extremity of the frame, a horizontally disposed shaft rotatably supported in such bearing, a propeller fixed to such shaft and disposed rearwardly of the body, a vertical shaft mounted in such bearing and the frame, and means for imparting axial movement to the vertical shaft.

In testimony whereof I hereunto affix my signature in the presence of two witnesses.

LOUIS F. E. VONDRAČEK.
